COMBINED SIFTING AND POURING SPOUT

Milton H. Klausmann, Maplewood, N. J., assignor
to Seal-Spout Corporation, Newark, N. J., a
corporation of New Jersey

Application November 4, 1950, Serial No. 194,133

1 Claim. (Cl. 222—480)

1

This invention relates in general to containers or receptacles of the type wherein a combined closure and pouring spout is connected to one wall of the container for movement relatively thereto so as in one position to serve as a closure for a pouring opening in said wall and in another position to serve as a spout for pouring the contents of the container through said opening. A pouring spout of this character usually comprises a body portion of a size and shape to close the pouring opening in the container, and integral sector-shaped side wings projecting approximately at right angles to the body portion that slide into and out of said opening in frictional engagement with the walls thereof as the spout is actuated to close and open said openings.

A prime object of the invention is to provide a novel and improved combination of a pouring spout of this character and a sifter so related to each other and to the pouring opening of the container that the contents of the container selectively can be poured or sifted through the pouring opening.

Another object of the invention is to provide such a device which shall include a simple and reliable combination of only two parts one of which constitutes a screen whereby the contents of a container to which the device is attached can be poured directly in a stream through the pouring opening or shaken or sifted through said screen.

Other objects, advantages and results of the invention will be brought out by the following description in conjunction with the accompanying drawings in which

Figure 1 is a top plan view of a pouring spout and container embodying the invention showing the device in closed position;

Figure 2 is an enlarged fragmentary transverse vertical sectional view approximately on the plane of the line 2—2 of Figure 1;

Figure 3 is an enlarged fragmentary top plan view of the container and the pouring and sifting device showing the closure spout in open position;

Figure 4 is a view similar to Figure 2 on the plane of the line 4—4 of Figure 3;

Figure 5 is an enlarged fragmentary bottom plan view of the parts shown in Figure 1;

Figure 6 is an enlarged transverse vertical sectional view on the plane of the line 6—6 of Figure 1;

Figure 7 is a similar view showing the closure and closure-spout in open position and the sifting screen in position for sifting;

2

Figure 8 is a like view showing both the closure-spout and the sifting screen in open position for freely pouring the contents of the container through the pouring opening;

Figure 9 is a transverse vertical sectional view on the plane of the line 9—9 of Figure 5, and

Figure 10 is a similar view on the plane of the line 10—10 of Figure 5.

Specifically describing the illustrated embodiment of the invention, the reference character 1 designates the body portion of a container at one end of which is a cap 2 forming an end wall. The container may be formed of any suitable material such as cardboard, fiber board, or the like, and one wall of the container, usually the end wall 2, is provided with a substantially rectangular discharge aperture 3 and a tab 4 integrally connected to said wall at one end of the aperture for hinging movement into and out of the opening for a purpose to be described.

Cooperating with the container 1 is a pouring spout 5 hingedly connected to the wall 2 at one end of the opening so as to overlie and close said opening when in one position and to uncover or open said opening when in another position. The spout is preferably formed of thin sheet metal bent upon itself to form a flat body portion 6 and sector-shaped side walls 7 at the side edges of said body portion that have arcuate outer edges 8 concentric with the axis of swinging of the spout. The spout is of the same width as the aperture or opening 3 so as to frictionally engage the outer faces of the side walls 7 with the side edges of said aperture, and the body portion 6 at one end overlies the tab 4 and at its other end has an extension 9 beyond the corresponding end of the aperture 5 for a purpose to be explained. The spout may be hingedly connected to the wall 2 in any suitable manner but as shown, a pair of prongs or teeth 10 project from one end of the body portion 6 through the wall 2 and are bent or clinched so as to permit swinging movement of the spout and at the same time prevent the spout from being pulled out of the opening 3. As usual the outer ends 8 of the side walls or wings 7 are provided with lugs 11 to engage the underside of the wall 2 for preventing swinging movement of the spout outwardly of the opening 3, the extension 9 limiting movement of the spout in the other direction.

A perforated plate or screen 12 has one end secured to the tab 4 in any suitable manner as by a prong 13 which projects from the plate, penetrates the tab and is clinched thereover as best shown in Figures 5 and 6. The tab is depressed into the aperture so that the correspond-

ing end of the plate 12 may underlie the body portion 6 of the closure-spout when the latter is in its closed position, shown in Figure 6, and the plate 12 is of such length that its other end may project beyond the corresponding end of the opening 3 so as to completely overlie the opening as shown in Figure 6. With this construction, it will be seen that the screen or plate 12 can be swung about the tab 4 as a hinge so as to overlie the opening 3 as shown in Figures 6, 8 and 9 or be pulled away from the opening as shown in Figure 8. The plate 12 preferably has side flanges 14 to frictionally engage the inner surfaces of the side walls or wings 7 of the spout; and suitable stops for releasably holding the plate 12 in overlying relation to the pouring opening 3 may be provided, such as protuberances 15 in the flanges 14 to engage the inner side of the end wall 2 of the container.

In operation of the device, normally the plate 12 and the spout 5 will be arranged in overlying or closing relation to the pouring opening 3 as shown in Figures 1, 2 and 6. Should it be desired to sift or shake the contents of the container through the pouring opening 3, the spout 5 may be swung out of the opening and away from the plate 12 as shown in Figures 3, 4 and 7. During the outward movement of the spout, the plate 12 will be held against movement by the stop protuberances 15. Then by inverting the container and shaking it, the contents will be sifted or sprinkled through the apertures of the plate 12.

Should it be desired to pour the contents of the container freely through the opening 3, both the spout and the plate 12 may be swung outwardly away from the opening 3 as shown in Figure 8. This operation can be easily effected by applying lifting pressure to the free end of the plate 12, said pressure swinging the plate 12 and through contact of the plate with the body portion of the spout, also swinging the spout at the same time. Similarly both the plate 12 and the spout may be swung into closed position simultaneously by pressure against the body portion 6 of the spout tending to force the side walls 7 into the opening.

It will be observed by those skilled in the art that the device embodying the invention is adaptable to containers for either powdered or granular materials, it being possible to use the sifting plate 12 alone for dispensing powdered materials, and the dispensing plate being easily

4
moved out of the way for pouring granular materials through the pouring opening 3.

While the now preferred embodiment of the invention has been illustrated and described, it should be understood that the device may be used with other types of containers and may be structurally varied, all within the spirit and scope of the invention.

I claim:

- 10 The combination with a container having a substantially rectangular discharge aperture in one wall thereof, of a tab hingedly connected to said wall at one end of the aperture for swinging movement into and out of said aperture, a pouring spout hingedly connected at one end to said wall adjacent the hinging of said tab to open and close said aperture and comprising a body portion overlying said tab with one end portion adapted to project beyond the free end of said tab and the other end of said aperture for engagement with said wall in the closed position of the spout to limit closing movement of the spout and to seal said outer end of said aperture, and sector shaped side walls on said body portion having their outer faces frictionally engaging the side edges of said aperture to seal said edges in the closed position of said spout, and a perforate sifting plate fastened at one end to said tab for movement therewith to cover and uncover said aperture, said plate being of a size to project beyond the end of said aperture opposite said tab for engagement with said wall when the plate is in position to cover said opening, said plate also having side flanges frictionally engaging the side walls of said spout to form a seal between said plate and said spout.

MILTON H. KLAUSMANN.
